CONVERSION OF DIMETHYL ETHER

Everett Gorin, Woodbury, N. J., and Manuel H. Gorin, San Francisco, Calif., assignors, by mesne assignments, to Socony-Vacuum Oil Company, Incorporated, New York, N. Y., a corporation of New York

Application November 18, 1946, Serial No. 710,476

8 Claims. (Cl. 260—668)

1

This invention relates to the conversion of dimethyl ether to normally liquid hydrocarbons. More particularly, this invention relates to a process for the conversion of a mixture of dimethyl ether in the presence of a predominantly isobutane diluent to a mixture of normally liquid hydrocarbons predominantly of the isoparaffinic and aromatic types.

Various methods of producing normally liquid hydrocarbons synthetically are known to the art. Probably the most commonly known method is the catalytic hydrogenation of carbon monoxide and the simultaneous condensation of the hydrocarbon product to normally liquid hydrocarbon mixtures as exemplified by the Fischer-Tropsch process. Another method is to chlorinate normally gaseous hydrocarbons which are then converted to liquid hydrocarbons and hydrogen chloride by-products in a thermal condensation reaction. Such a process is taught in U. S. Patent 2,320,274. Various modifications of the former method produce highly olefinic, straight chain hydrocarbons or normal paraffinic hydrocarbons of low antiknock value when used as motor fuel. The latter process requires relatively high temperatures in the alkyl chloride condensation step and also requires corrosion resistant materials of construction due to the formation of hydrogen chloride by-products.

The present condensation process requires only moderate temperatures in the conversion of dimethyl ether to liquid hydrocarbons and no corrosive by-product is formed in the reaction. The liquid product consists primarily of aromatic hydrocarbons and isoparaffinic hydrocarbons suitable for incorporation in motor fuel.

An object of this invention is to provide an improved process for the synthesis of normally liquid hydrocarbons. Another object of the invention is to produce synthetically a mixture of normally liquid hydrocarbons containing a relatively high percentage of isoparaffinic and aromatic hydrocarbons. Still another object of the invention is to catalytically condense dimethyl ether to produce normally liquid hydrocarbons suitable for incorporation in motor fuel. A further object of the invention is to catalytically condense dimethyl ether in the presence of isobutane and normally gaseous olefinic hydrocarbons to produce high yields of normally liquid hydrocarbons. Other objects will be apparent from the description of the invention.

We have found that dimethyl ether can be converted to hydrocarbons containing two or more atoms of carbon per molecule in the presence of

2

synthetic alumina catalyst or synthetic alumina-silica catalyst. The conversion is preferably carried out in the presence of isobutane diluent to obtain a high yield of normally liquid hydrocarbons. Dimethyl ether may be readily prepared in high yields from methanol intermediate by catalytic dehydration. Dimethyl ether may also be produced directly from synthesis gas by the choice of a suitable catalyst although more or less methanol will be produced simultaneously. Since methanol may be readily produced from synthesis gas, obtainable by the reaction of steam with natural gas or coal, or by partial oxidation of methane, our invention provides an indirect method for the conversion of coal or natural gas to normally liquid hydrocarbons.

The condensation of dimethyl ether is effected with the aid of catalysts which exhibit pronounced polymerization and dehydration activity. 20 Metallic oxide type contact catalysts which have surfaces of acidic character may be employed advantageously for the promotion of the condensation reaction. Acid-leached aluminas constitute one type of catalyst which may be used. The alumina catalyst may be prepared by leaching commercial activated alumina gel with an organic acid such as formic acid or acetic acid or with an inorganic acid such as hydrofluoric acid, phosphoric acid, or boric acid. The acid-leached alumina is then dried at 100° C. and reactivated by heating at a temperature of about 500° C. for several hours.

A second group of catalysts which are particularly effective in our process consists of associations of alumina and silica, which combination of oxides may also contain one or more oxides of metals of groups II, III, and IV of the periodic table such as beryllium oxide, magnesium oxide, boron oxide, lanthanum oxide, zirconium oxide, and thorium oxide. It is essential that the catalyst does not contain significant quantities of oxides of other groups of the periodic table. Alkali metal oxides and other strongly alkaline oxides destroy the activity of the catalyst. Oxides which show catalytic activity with respect to hydrogenation also should be excluded from the reaction zone. Such oxides as the oxides of chromium or molybdenum oxide as well as the oxides of metals of the transition group such as iron oxide cause extensive decomposition of the methyl ether to such undesirable products as free carbon, methane, and the oxides of carbon.

We prefer a catalyst consisting of an association of silica with a minor amount of alumina. The catalyst may be prepared by several methods

well known in the art. Thus, silica gel, substantially free of alkali metal oxides, may be impregnated with an aqueous solution of an aluminum salt or the silica and alumina may be coprecipitated by the addition of aluminum sulfate solution to a solution of sodium silicate. The precipitate is then washed with water and dilute mineral acid to remove sodium ions from the surface. It is then dried and heated to activate the mixture.

Our preferred catalyst is prepared by ball milling washed moist silica hydrogel with alumina hydrogel, drying the mixture of hydrogels at about 100° C. and activating the mixture at about 500° C. The alumina hydrogel is preferably prepared by forming the alumina hydrosol. A mercury-aluminum amalgam is digested in a dilute solution of an organic acid such as acetic or formic acid. The clear hydrosol is separated from the amalgam and set to the hydrogel by any of the methods well known in the art. Silica hydrogel may be prepared by the addition of a sodium silicate solution to an excess of mineral acid or acetic acid. The mol ratio of silica to alumina in the finished catalyst may vary from about 5 to 35 mols, preferably from about 5 to about 15 mols of silica per mol of alumina.

The above catalysts are active for the condensation of dimethyl ether at temperatures within the range of from about 300° C. to about 475° C. Temperatures in excess of 475° C. are unsuitable due to excessive decomposition of the products. Our preferred temperature range for operating the condensation reaction in the presence of the alumina-silica catalyst is from about 350° C. to about 425° C. Pressures within the range of from about 50 pounds to about 800 pounds per square inch gage, or even higher, may be used. We prefer to operate the condensation reactor at pressures within the range of from about 150 pounds to about 500 pounds per square inch gage.

When pure dimethyl ether is passed over an alumina-silica catalyst considerable amounts of undesirable by-products such as methane, the oxides of carbon and free carbon are formed. However, we have found that the formation of these products can be substantially suppressed and the yield of liquid hydrocarbons can be substantially increased by carrying out the conversion of the ether in the presence of a diluent. The term "diluent" as used in the specification and claims refers to a normally gaseous hydrocarbon containing not more than four carbon atoms per molecule or a mixture of such hydrocarbons, which hydrocarbons may or may not be reacted under the conditions of operation of the process. At least a part of the diluent may be obtained by recycling the primary reaction products consisting of C₂, C₃, and C₄ hydrocarbons. Isobutane is particularly effective in reducing the amount of carbon and methane formed. The process can be operated under conditions such that no isobutane is consumed or, if desired, sufficient concentration of isobutane diluent may be used to promote alkylation thereof with the ether and/or the light olefins produced in the process.

When operating our process to avoid consumption of isobutane in the reaction we maintain a mol ratio of isobutane to dimethyl ether in the reaction zone not greater than about 6 to 1. Higher ratios up to about 20 to 1 are beneficial in suppressing the formation of carbon and methane. The higher ratios of isobutane to ether produce a corresponding increase in the amount

of normally liquid hydrocarbons in the product and an increase in the isobutane consumed as a result of the alkylation reaction. Preferably, a ratio of at least one mol of isobutane to one mol of dimethyl ether feed to the reaction zone should be present in the reaction zone.

It is advantageous to recycle the normally gaseous hydrocarbon product having two or more atoms of carbon per molecule which consists of

- 10 C₂, C₃, and C₄ olefins and paraffins. The olefinic content of these fractions tends to increase with increasing temperature, and tends to decrease with increasing pressure and/or percentage conversion per pass. For economic reasons, we
- 15 prefer to operate with space velocity, temperature and pressure adjusted to give a relatively high conversion of the dimethyl ether per pass, that is, from about 70 per cent to about 95 per cent or even higher. Space velocities should be adjusted to a value within the range of from about 1 to 40 volumes of total feed per volume of catalyst space per minute when operating at temperatures of from about 300° C. to about 475° C. and pressures of 50 to 800 pounds per square inch.
- 20 When operating with our preferred alumina-silica catalyst at temperatures in the range of from 350° C. to 425° C. and pressures of from 150 to 500 pounds per square inch, space velocities within the range of from 3 to about 20 volumes of
- 25 total feed to the reactor per volume of free catalyst space per minute should be used. The volume of total feed is defined as the volume of dimethyl ether plus isobutane diluent and recycle gas, other than isobutane, measured as a gas
- 30 under standard conditions of temperature and pressure. Total feed also includes any methanol present in the feed to the process.

As indicated hereinabove the chief source of dimethyl ether feed to our process is from methanol. The decomposition of methanol to form dimethyl ether produces an equilibrium mixture containing about 85 to 95 mol per cent dimethyl ether and 5 to 15 mol per cent methanol, depending on the temperature employed. We have found that methanol in the presence of isobutane diluent can be converted directly to C₂₊ hydrocarbons in the presence of the alumina-silica catalyst. However, the conversion of methanol proceeds more slowly and the yield of normally liquid hydrocarbons is much lower than is obtained when dimethyl ether is condensed in the absence of methanol. We may use up to 20 mol per cent of methanol in the dimethyl ether feed to the process, although we prefer to first separate the methanol from the dimethyl ether when obtaining the ether feed by the dehydration of methanol intermediate.

The invention will be more clearly understood from the following detailed description of one embodiment of our invention illustrated by the drawing which forms a part of the specification.

Referring now to the drawing, towers 1 and 2 contain alumina gel-silica gel catalyst either as a continuous bed or disposed in trays. We prefer the latter method of packing these towers, since the difficulty of controlling regeneration temperatures is reduced if the catalyst is maintained in a series of relatively shallow beds. Towers 1 and 2 are manifolded in such manner that while one of these towers is on stream for the condensation reaction the catalyst in the other tower is available for the regeneration, thus providing for substantially continuous operation.

Liquid dimethyl ether which may contain up

to 20 mol per cent of methanol is introduced to the process through line 10 by means of pump 11 in line 12 which connects with line 10. Isobutane diluent is introduced to line 12 from line 13 and the mixture is passed at a pressure of from about 150 pounds to about 500 pounds per square inch through lines 16 and 18, and heat exchangers 15, 17, and 19 wherein heat is absorbed from the reaction product in lines 25 and 26 and from hot regeneration gases in line 27. From exchanger 19 the hot feed passes via line 28 to manifold line 30 provided with valves 31 and 32 and connected with reactor feed manifold lines 33 and 34. With valve 31 in line 30 open and valve 32 closed, the vaporized feed mixture is introduced to tower 1 through a multiplicity of valved feed lines leading from line 33. By introducing the feed stream to reactor 1 as a multiplicity of streams we avoid a high instantaneous concentration of the dimethyl ether at any one point in the reaction zone and thus direct the reaction toward the formation of normally liquid hydrocarbons. The temperature of the reaction mixture as it enters the reaction zone is within the range of from about 350° C. to 425° C. and the space velocity as defined hereinabove is adjusted to react at least 70 per cent of dimethyl ether per pass through the reaction zone.

The dehydration-condensation of dimethyl ether is a mildly exothermic reaction. Hence, we introduce at least a part of the diluent to reactor 1 in the form of a relatively cold gas consisting of a major amount of ethylene and minor amounts of methane and propylene. This recycle gas is introduced from line 35 which joins manifold line 36. Line 36 is provided with valve 37, which is open for transfer of diluent, and with valve 38, which is closed.

The product from reactor 1 consists substantially of a mixture of ethylene, propylene, propane, isobutane, normal butane, normal butylenes, normally liquid hydrocarbons, water vapor, a small amount of unreacted dimethyl ether together with small amounts of methane, hydrogen and carbon monoxide. A small amount of methanol may also be formed by reaction of the ether with the water product. The product is passed through drawoff line 40, equipped with valve 39 which is closed, to manifold line 41 which is equipped with valves 42 and 43, the latter being closed and the former open for delivery of the product to line 25 leading to heat exchanger 17. In heat exchanger 17 the product is subjected to initial cooling. From exchanger 17 the product passes via line 26 to exchanger 15 where the product is further cooled by heat exchange with the feed. The product passes from exchanger 15 via line 44 to cooler 45 wherein it is condensed to a mixture containing liquid carbons of less volatility than methane. The condensed mixture also contains dissolved unreacted dimethyl ether and methyl alcohol and water. The mixture and uncondensed methane, carbon monoxide and hydrogen pass from cooler 45 through line 46 to settler 50 wherein the uncondensed components and water are separated from the liquid hydrocarbon components of the product.

Settler 50 is provided with valved gas release line 51 for the elimination of hydrogen and at least a part of the carbon monoxide and methane from the product. Generally, the amount of these products in the product mixture is small, particularly where a relatively large amount of isobutane diluent is incorporated in the feed.

The amount of water vapor produced in reactor 75

by the dehydration of the dimethyl ether is considerable and hence the water phase in settler 50 will contain a considerable part of the unreacted dimethyl ether and also a major part of any unreacted methanol. Water is withdrawn from settler 50 through drawoff line 52 and the dimethyl ether and methanol dissolved therein are recovered by fractionation and recycled to line 10.

The non-aqueous liquid product in settler 50 is passed to heater 53 by means of pump 54 in line 55 and thence through line 56 to fractionating system 60 wherein the normally gaseous, predominantly olefinic condensation products and isobutane diluent are separated from the liquid hydrocarbon product of the condensation reaction. Fractionation system 60 may consist of one or more than one fractionator which may be operated to include the normal C₄ hydrocarbons in the normally liquid hydrocarbon stream. However, we prefer to include these C₄ hydrocarbons in the recycle stream to the reaction zone and to eliminate them with the product stream only when the normal butane in the recycle stream builds up to an undesirable concentration. Generally, the normal C₄ hydrocarbons are included in the overhead normally gaseous product stream since the amount of normal butane in the product is relatively small and the butylenes are preferably recycled to the reaction zone where, in the presence of isobutane, they react to increase the yield of normally liquid hydrocarbons. The liquid product from fractionation system 60 is withdrawn through valved line 61 and is passed to additional processing steps for the production of motor fuel. The remainder of the product consisting of normally gaseous hydrocarbons and any unreacted dimethyl ether passes overhead from fractionation system 60 through line 62 to condenser 63 and thence through line 64 to reflux accumulator 65. The gaseous product in accumulator 65 consisting substantially of C₂ hydrocarbons, a minor amount of propylene, and any residual methane passes overhead through line 66. This product may be eliminated from the system through valved line 67. We prefer to recycle the vapor stream through valved line 35 by means of compressor 68 since the ethylene and propylene content of the stream constitutes valuable diluent for the production of increased yields of product in reactor 1.

The liquid product from accumulator 65 is picked up by pump 70 in line 71 and a part of the stream is passed through line 72 to fractionation system 60 for use as a reflux. The remainder of the condensed product is directed through line 73 and at least a part of the stream is recycled via valved line 74 to reactor feed line 12. A part of the condensed product in line 73 may be directed, either continuously or intermittently, through valved line 75 to depropanizer 80 wherein that part of the product of lower volatility than the C₃ hydrocarbons is separated from the C₃ hydrocarbons. The less volatile stream of hydrocarbons consisting substantially of a major proportion of isobutane and a minor amount of normal C₄ hydrocarbons and which also may contain a small amount of unreacted dimethyl ether, is withdrawn from depropanizer 80 through line 81 by means of pump 82. At least a part of this stream may be withdrawn from the process through line 83 to avoid excessive buildup of the C₄ hydrocarbons in the system. However, we prefer to recycle the stream through line 84 to isobutane feed line 13. The overhead product from depropanizer 80 consisting substantially of

propylene and any residual ethylene passes overhead through line 85 to condenser 86 and thence via line 87 to reflux accumulator 90. Condensed propylene and ethylene in accumulator 90 are removed therefrom by means of pump 81 in line 92 and are passed in part via line 83 to tower 80 for use as reflux. The remainder of the olefins is passed through line 94 to line 84 and thence to isobutane feed line 13. If desired, propylene and ethylene may be eliminated from the system through line 85 if the concentration of these hydrocarbons in the system becomes excessive. Propane is withdrawn from depropanizer 80 as a side stream through trapout line 98.

After reactor 1 has been on stream for an interval up to 90 minutes depending on the operating conditions relative to temperature, pressure and amount of diluent in the feed, sufficient carbon will have accumulated on the catalyst to necessitate reactivation. This is accomplished by passing air through the reactor, the air being diluted with flue gas in order to control the rate of oxidation and thereby maintain the regeneration temperature below about 650° C., preferably below about 600° C. However, reactor 1 and the catalyst therein will contain residual dimethyl ether, diluent in the form of gas and residual gases which must be removed before the oxidation of the carbon from the catalyst is attempted. The purge gas may suitably consist of oxygen-free flue gas and/or steam. If desired, the main purging operation may be preceded with a preliminary purge with a dry natural gas consisting substantially of methane and ethane.

Reactor 1 is isolated for purging by opening valves 39 and 100 in lines 40 and 101 respectively, and closing valve 103 in line 102, valve 31 in line 30, valve 37 in line 36, valve 104 in line 105, valve 106 in line 107, valve 42 in line 41, and valve 108 in line 109. With valve 114 in line 115 and valve 116 in line 102 in the open position purge gas is introduced to the system through line 116 and is passed through lines 102 and 36 to reactor 1 for the removal of residual dimethyl ether and hydrocarbon vapors. The mixture of gases passes through line 40 to line 101 and thence from the system.

After reactor 1 has been purged the following valves are adjusted to isolate the reactor for the oxidative regeneration step. Valve 117 in line 107, valve 38 in line 40, valve 118 in line 102 and valve 119 in line 105 are closed. Valve 104 in line 106, valve 108 in line 107 and valve 119 in line 120 are placed in the open position. Air diluted with flue gas is then introduced to the system through line 124 by means of compressor 125 and is passed through lines 105 and 38 to reactor 1. Carbon is burned from the catalyst surface and the hot regeneration gases pass from the reactor and from the system through lines 40, 107, 27, and 120. At least a part of the regeneration gas may be recycled to line 124 by adjusting valve 119 in line 120 and opening valve 126 in line 127 which connects with line 124. When the reactivation of the catalyst in reactor 1 is complete the reactor is again purged with relatively cold oxygen-free flue gas or steam and the reactor is then in condition for reuse in the reaction step of the cycle. While reactor 1 is on stream for regeneration, reactor 2 is in service for the dehydratation-condensation of the methyl ether.

The above description of the process is simply illustrative of the invention and is subject to many modifications by those skilled in the art. Thus, instead of using fixed bed reactors we may

use fluidized powdered catalyst in hindered settling technique in the reaction cycle or in the regeneration cycle. We may also adapt other methods of catalytic contacting to our process of converting dimethyl ether to normally liquid hydrocarbons. For example, the various types of moving catalyst bed techniques well known in the hydrocarbon conversion art may be used if relatively low pressure operation is followed. However, we prefer to operate the process at pressures within the range of from about 150 to 500 pounds per square inch in order to obtain higher yields of saturated normally liquid hydrocarbon products.

For the better understanding of our invention the following example illustrating the same is given. It is understood that this example is illustrative only and in no way limits the scope of the invention.

EXAMPLE

An alumina-silica catalyst was prepared according to the following method. Alumina gel was prepared by digesting aluminum amalgam in 1% acetic acid to form a clear hydrosol. The hydrosol was gelled by the addition thereto of a dilute ammonia solution. Silica hydrosol was prepared by the addition of sodium silicate solution to an excess of sulfuric acid solution, the solution mixture being stirred and cooled during the mixing operation. The moist hydrosols were washed with distilled water and then ballmilled together to form an intimate mixture and the mixture was dried at about 100° C. The dried mixture of gels was activated by calcining at about 500° C. for several hours. The finished catalyst contained 7 mols of silica per mol of alumina.

A mixture consisting of 18.2 mol per cent of dimethyl ether and 81.8 mol per cent of isobutane was passed over the above alumina-silica catalyst at a temperature of 370° C. and a pressure of 150 pounds per square inch gage and a space velocity of 6.8 volumes of gaseous mixture per volume of catalyst space per minute. The dimethyl ether was reacted to the extent of 94.5 per cent to give a product gas, the analysis of which is given in column two of the table below. The yield of the different products in per cent of the theoretical based on the ether decomposed is given in the third column of the table.

Table

55	Component	Vol. Per Cent of Effluent Gas	Yield Per Cent of Theoretical
	H ₂ + CO	Trace	-----
	C ₁	1.43	5.7
	C ₂	1.36	10.2
	C ₃ + plus C ₄	0.72	8.1
	(CH ₃) ₂ O	0.37	-----
60	1- ₂ C ₄ H ₉	93.03	-----
	n-C ₄ + plus n-O ₂	0.35	5.2
	1-C ₅	1.42	26.4
	1-C ₆	0.48	11.0
	C ₇	0.12	3.0
	C ₈ +	0.72	21.6
65	Carbon	-----	8.6
		100.00	99.8

The above results indicate that 85.7 per cent of the carbon content of the dimethyl ether feed which reacted, appeared in the product as C₂+ hydrocarbons and that 62.0 per cent of said carbon content was converted to C₅+ hydrocarbons. There was no significant amount of isobutane produced by or consumed in the reaction.

70 A similar experiment wherein pure dimethyl

ether was passed over the same catalyst at a higher temperature, lower pressure and higher space velocity resulted in a gaseous product containing a considerably higher proportion of methane and carbon monoxide while the yield of C_5+ hydrocarbons was somewhat less than 15%. The yield of free carbon was also quite high when pure dimethyl ether, undiluted with isobutane, was used as feed to the reactor.

This invention is not limited by any theories of mechanism of the reactions nor by any details which have been given merely for purpose of illustration but is limited only in and by the following claims in which it is intended to claim all novelty inherent in the invention.

We claim:

1. The process for the conversion of dimethyl ether to normally liquid hydrocarbons which comprises the steps of (1) passing a feed stream comprising dimethyl ether and a normally gaseous hydrocarbon diluent containing at least two carbon atoms and not more than four carbon atoms per molecule in contact with a dehydration-polymerization catalyst at a temperature within the range of from about 300° C. to about 475° C. to form a product mixture comprising methane, normally gaseous hydrocarbons containing from 2 to 4 carbon atoms per molecule, normally liquid hydrocarbons, and water, (2) separating methane and water from the product mixture of step 1, (3) fractionating the residual hydrocarbon product from step 2 to obtain a stream consisting substantially of normally liquid hydrocarbons and at least one stream of normally gaseous hydrocarbons containing from 2 to 4 carbon atoms per molecule, (4) recycling the stream of normally gaseous hydrocarbons of step 3 to step 1, and (5) recovering said normally liquid hydrocarbons from step 3 of the process.

2. The process for the conversion of dimethyl ether to normally liquid hydrocarbons which comprises the steps of (1) passing a feed stream consisting substantially of from about 1 mol to about 20 mols of isobutane per mol of dimethyl ether in said feed stream in contact with an alumina gel-silica gel catalyst at a temperature within the range of from about 300° C. to about 475° C. to form a product mixture comprising methane, normally gaseous hydrocarbons containing from 2 to 4 carbon atoms per molecule, normally liquid hydrocarbons, and water, (2) separating methane and water from the product mixture of step 1, (3) fractionating the residual hydrocarbon product from step 2 to obtain a stream consisting substantially of normally liquid hydrocarbons and at least one stream of normally gaseous hydrocarbons containing from 2 to 4 carbon atoms per molecule, (4) recycling stream of normally gaseous hydrocarbons from step 3 to step 1, and (5) recovering said normally liquid hydrocarbons from step 3 of the process.

3. The process for the conversion of dimethyl ether to normally liquid hydrocarbons which comprises the steps of (1) passing a feed stream consisting substantially of dimethyl ether and isobutane in the ratio of at least one mol of isobutane and not more than 6 mols of isobutane to one mol of dimethyl ether in said stream in contact with alumina gel-silica gel catalyst in a reaction zone at a temperature within the range of from about 350° C. to about 425° C. and at a pressure within the range of from about 50 pounds to about 800 pounds per square inch to form a product mixture comprising normally liquid hydrocarbons, normally gaseous hydrocarbons, and

water, (2) separating water from the product mixture of step 1, (3) fractionating the hydrocarbons obtained in step 2 to obtain a stream consisting substantially of normally liquid hydrocarbons and at least one stream of normally gaseous hydrocarbons containing from 2 to 4 carbon atoms per molecule, (4) fractionating the normally gaseous hydrocarbons obtained in step 3 to obtain at least one stream of normally gaseous olefinic hydrocarbons containing at least 2 carbon atoms per molecule and a stream consisting substantially of isobutane, (5) recycling at least a part of each of the olefinic hydrocarbon fractions and isobutane fraction obtained by step 15 to step 1, and (6) recovering said normally liquid hydrocarbons from step 3 of the process.

4. The process as described in claim 3 wherein the space velocity of the total feed through the reaction zone of step 1 is within the range of from about 3 to about 20 volumes of total gases including the dimethyl ether feed, isobutane diluent and recycle olefins per volume of free catalyst space per minute.

5. The process for the conversion of dimethyl ether to normally liquid hydrocarbons which comprises the steps of (1) passing a feed stream comprising a mixture of dimethyl ether and methyl alcohol containing at least 80 mol per cent of dimethyl ether together with isobutane diluent 25 in an amount equal to at least one mole of isobutane per mol of dimethyl ether and methyl alcohol in said mixture through a reaction zone in contact with alumina gel-silica gel catalyst at a temperature within the range of from about 350° 30 C. to about 425° C. to form a product mixture comprising normally liquid hydrocarbons, normally gaseous hydrocarbons, water, and unreacted methyl alcohol, (2) separating water and methyl alcohol from the hydrocarbons of step 1, 35 (3) fractionating the hydrocarbons obtained in step 2 to obtain a stream consisting substantially of normally liquid hydrocarbons and at least one stream of normally gaseous hydrocarbons, (4) recycling at least a part of the normally gaseous 40 hydrocarbon stream of step 3 to step 1, and (5) recovering said normally liquid hydrocarbons from step 3 of the process.

6. The process for the conversion of dimethyl ether to normally liquid hydrocarbons which comprises the steps of (1) passing a feed stream comprising dimethyl ether and a hydrocarbon diluent containing from 2 to 4 carbon atoms per molecule in contact with a dehydration-polymerization catalyst comprising alumina gel at a temperature within the range of from about 300° C. to about 475° C., (2) condensing at least a part of the reaction mixture of step 1 to form a mixture consisting substantially of normally liquid hydrocarbons, normally gaseous hydrocarbons, water, and unreacted dimethyl ether, (3) separating water and at least a part of the unreacted dimethyl ether from the mixture obtained in step 2, (4) separating the normally liquid hydrocarbons from the normally gaseous hydrocarbons obtained in step 2, and (5) recovering said normally liquid hydrocarbons from step 4 of the process.

7. The process for the conversion of dimethyl ether to normally liquid hydrocarbons which comprises the steps of (1) passing a feed stream comprising dimethyl ether and a hydrocarbon diluent containing from 2 to 4 carbon atoms per molecule in contact with the dehydration-polymerization metallic oxide contact type catalyst containing alumina gel and silica gel at a temperature 70 within the range of from about 300° C. to about 75

11

475° C. to react at least 70 per cent of said dimethyl ether, (2) condensing at least a part of the reaction mixture of step 1 to form a mixture consisting substantially of normally liquid hydrocarbons, normally gaseous hydrocarbons, water, and unreacted dimethyl ether, (3) separating water and at least a part of the unreacted dimethyl ether from the mixture obtained in step 2, (4) separating the normally liquid hydrocarbons from the normally gaseous hydrocarbons obtained in step 2, and (5) recovering said normally liquid hydrocarbons from step 4 of the process.

8. The process for the conversion of dimethyl ether to normally liquid hydrocarbons which comprises passing a stream consisting essentially of dimethyl ether in contact with a metallic oxide contact type catalyst at a temperature within the range of from about 300° C. to about 475° C. in a reaction zone to form a product mixture con-

10

15

12

taining normally liquid hydrocarbons, normally gaseous hydrocarbons, and water, separating water from the product mixture of hydrocarbons, and fractionating the hydrocarbons from said product mixture to obtain a stream containing said normally liquid hydrocarbons and at least one stream of normally gaseous hydrocarbons.

and that the said Letters Patent should be read with these corrections therein that the same may conform to the record of the case in the Patent Office.

Signed and sealed this 7th day of June, A. D. 1949.

[~~SEAL~~]

THOMAS F. MURPHY,
Assistant Commissioner of Patents.
